Patented Apr. 20, 1971

220,547

COMBINED PHONOGRAPH AND RADIO OR SIMILAR ARTICLE

Donald E. Leman, Rosemont, Ill., assignor to Ampex
Corporation, Redwood City, Calif.

Filed May 8, 1970, Ser. No. 22,899

Term of patent 14 years

Int. Cl. D14—03

U.S. Cl. D56—4

The sole figure is a front, top and right side perspective view of a combined phonograph and radio or similar article, showing my new design, the left side being a mirror image of the right side, the right door panel being identical to the left door panel, and the back and bottom being conventionally plain.

Portions of the drawing figures have been diagonally lined to indicate transparency and portions have been lined and stippled to indicate contrast in appearance.

I claim:

The ornamental design for a combined phonograph and radio or similar article, substantially as shown and described.
